UNITED STATES PATENT OFFICE.

HARRY F. SMITH, OF EASTON, PENNSYLVANIA.

FAN AND CONE-TRAY.

1,187,396.

Specification of Letters Patent. Patented June 13, 1916.

Application filed July 15, 1915. Serial No. 40,039.

To all whom it may concern:

Be it known that I, HARRY F. SMITH, a citizen of the United States, residing at Easton, in the county of Northampton and State of Pennsylvania, have invented certain new and useful Improvements in Fans and Cone-Trays; and I do hereby declare the following to be a full, clear, and exact description of the invention, such as will enable others skilled in the art to which it appertains to make and use the same.

While this invention is primarily intended for an advertising novelty, in the condition in which it is given away it relates to toilet fans, and in the condition to which it is altered and the use to which it is put by the recipient it relates to trays for carrying long narrow articles and especially ice-cream cones. From this statement it may be gathered that the purpose of this invention is to produce a cheap and attractive novelty for a retailer as for instance the proprietor of a soda fountain or summer garden where ice-cream cones are sold, bearing on it his advertisement, directions for using the device, and possibly other matter such as a list of his soda flavors, creams and ices, etc.—all printing being omitted from the drawings and the following specification, as the purchaser is at liberty to order such printing as he may desire. The specific use of the device will be more fully explained below. In structure it is initially a fan, and as such it must have a blade and a handle; but as it subsequently becomes a tray for transporting ice-cream cones through the street, it is desirable that it have a cover for such cones so as to protect them from dust.

The device may be made in a variety of ways, some of which are described below and illustrated in the accompanying drawings, wherein:

Figure 1 is a perspective view of this novelty when used as a tray for carrying an ice-cream cone. Fig. 2 is a longitudinal section showing the cover sheet in full lines as attached at its free end to the handle, and in dotted lines as having been detached therefrom and raised as shown in full lines in Fig. 1. Fig. 3 is a bottom plan view of one type of this invention whose handle is of wire continued into a frame surrounding and supporting the blade, and the latter in this instance has a number of holes which are closed in various ways as will be de-

scribed. Fig. 4 is a cross section on line 4—4 of Fig. 3.

The essential features of a fan are a blade and a handle. While the meaning of the latter term is clear, the term "blade" as used herein is intended to differentiate from the blade of a knife or oar. It will be found from the description that the blade of this novelty has holes through it which are by preference initially closed, but even if they should all be open their aggregate area is considerably less than the area of the remaining portion of the blade, and for this reason the term "blade" is intended to differentiate from the similar part of a tennis racket, a fly swatter, etc. In other words, the blade of this device when its holes are closed is much like the blade of an ordinary fan and must have sufficient rigidity to permit it to be used in the same way, whereas with some or all of the holes open the device can yet be used as a fan by waving its blade in front of the face as usual.

The handle 1 shown in Figs. 1 and 2 is of wood, possibly split as at 2 and passed astride the blade and secured thereto by any suitable means such as tacks 3. The handle 4 in Fig. 3 is made of two stretches of wire coiled together, diverging from each other at the point 5 and carried completely around the blade so as to form a frame 6; and at a point or points within the frame this wire can be formed into reinforcing rings 7 for use as described below. I reserve the widest latitude as to the construction of the handle but prefer that it be light and cheap, while sufficiently stout to support the device when used as a tray and loaded to its capacity.

The blade 10 as shown in Figs. 1 and 2 is a piece of stout cardboard or similar stiff sheet material which as already suggested may be fastened within or to the handle 1 by tacks 3 or the like. The blade 11 shown in Figs. 3 and 4 is also of tough sheet material such as heavy paper, although in this case it may not have the stiffness of cardboard because its edges 12 are carried over and around the frame 6 and pasted to the body underneath as at 13 or stitched as at 14 in Fig. 4. In any type of my invention the blade is provided with a number of holes as best shown at 15 in Fig. 1, each hole being preferably round and of about one and one quarter inches in diameter so that an ice-cream cone 16 may be passed

part way through the hole and supported by the blade around it. I find it satisfactory to pierce the blade with two or perhaps three holes at each side of a central longitudinal line, and a single hole through said line near the outer end of the blade, but the number and disposition of the holes is entirely a matter of choice, and in fact if the device is small its blade may have but a single hole.

All the holes are by preference initially closed so that when the novelty is given away it is at first a fan, but here again it is quite possible to depart from this suggestion and leave some of the holes open, especially where the blade is large enough to have several, because in any case it is my intention that the aggregate area of the holes shall be less than the remaining portion of the blade. The closures for the holes are omitted from Figs. 1 and 2. In Fig. 3 the heavy paper constituting the blade 11 passes directly over the ring 7 and itself constitutes the closure for the hole which said ring defines. The paper 11 (or it might be the cardboard 10) is shown at 18 as scored on a circle so that the closure defined by this circle may be punched out by hand. The material of the blade is shown at 19 and 20 as cut on two approximate semicircles whose extremities are separated slightly so as to leave tongues 21 which retain the inclosed closure or disk 22 normally in place, but the latter may be removed by breaking the tongues. The hole indicated at 23 is shown as covered by a piece of thin paper 24 which may be pasted or otherwise attached to the blade 11, and when this hole is to be used the paper is punched out as shown at 25. The disk-like closure 26 within the hole indicated at 27 is shown as held therein by a strip of paper 28 extending across and pasted to the disk and with its extremities pasted to the blade, and to remove this closure the strip is torn off. These are but a few of various means which may be employed for covering the holes or holding their closures removably in place, but in any event the fastening means should be sufficiently strong to withstand the resistance of air when the device is waved back and forth in its use as a fan, while yet being sufficiently weak to be easily broken, torn, or ruptured by the operator, without the use of tools.

This novelty eventually becomes a tray for carrying ice-cream cones as already stated, and as the user will doubtless carry these wet cones from the point of purchase to his or her home it becomes desirable to cover them over while in transit so as to protect them from dust. To this end I employ a cover sheet shown at 30 in Fig. 1, and which may well be a piece of wax paper or the like passed over the outer end of

the blade at 31 and secured beneath the same as shown at 32. When this cover sheet is employed, it may be possible to omit some or all of the closures for the holes already described. That is to say, the sheet could be drawn tightly over the blade 10 as indicated at 30^a in Fig. 2, and its free or inner end possibly held initially under the heads of the tacks 3; and when the sheet is to be used it could be torn off said tacks and raised as indicated in dotted lines at 30^b. The specific use of this sheet is as a cover for the open upper end of the cones as shown in Fig. 1, and its free inner end may well be held from blowing out of place by pressing it down onto the handle 1 with the thumb.

This device is given away by the dealer as a novelty, and in use the recipient employs it initially as a fan and will be attracted by the mechanism and instructions so that any advertising printed upon the novelty will catch the eye. Assuming that two or three ice-cream cones are bought, the cover is raised (if the device have a cover) and this exposes the holes 15 if they are open, and if they are the cover will serve as their closure. But if the holes are closed in any of the various ways shown in Fig. 3, the user then removes the closure in the manner already set forth. The tip of the cone is then passed down through the hole until its body comes to rest therein, and if the hole happened to be reinforced by a ring 7 it is quite obvious that the moisture of the cream upon the cone will not affect the paper blade 11 so that it would tear undesirably and drop the cone in transit. Reaching home, the cones are removed, and yet the device is serviceable as a fan by laying the cover along the blade to close its holes, or it is serviceable as a fan even if it have no cover because the holes occupy the minor area of the blade. For these various reasons it will be seen that this novelty is attractive and interesting, it finds its use in warm weather either as a fan or a tray for ice-cream cones and as either it is serviceable as a price list for cooling drinks and cream, and after the recipient has carried it home as a tray it is still useful as a fan, and of course it retains the advertising as long as it lasts.

What I claim is:

1. A device for use as herein described, the same comprising a handle, a frame carried by the handle, a sheet stretched over and secured to said frame and provided with holes of a shape and size to receive ice-cream cones, removable closures for said holes, and a cover sheet secured at one end to the frame and of a length to extend over the same.

2. The herein described fan having a handle, a stiff blade provided with a round hole of a size to receive and support an ice-cream

cone, a closure for said hole, retaining means capable of rupture for holding the closure in position, and a cover sheet of wax paper secured at one end to the outer end of the blade and of a length sufficient to extend completely over the blade and onto the handle.

3. A device for use as herein described, the same comprising a handle, a wire frame connected with the handle and bent into a ring inclosed within the frame and of a size to receive and support an ice-cream cone, a sheet of material capable of being ruptured stretched over the frame and ring and secured around its edges to the former, and a cover sheet secured at one end to the frame and of a length to extend over the same.

4. A device for use as herein described, the same comprising a handle, a frame carried by the handle, a sheet stretched over and secured to said frame and provided with holes of a shape and size to receive ice-cream cones, and removable closures for said holes.

5. A device for use as herein described,

the same comprising a handle, a wire frame connected with the handle and bent into a ring inclosed within the frame and of a size to receive and support an ice-cream cone, and a sheet of material capable of being ruptured stretched over the frame and ring and secured around its edges to the former.

6. In a device for the purpose herein set forth, the combination with a handle, and a stiff blade having a hole; of a cover sheet secured at one end to the blade and of a length to extend over the same.

7. In a device for the purpose herein set forth, the combination with a handle, and a stiff blade having a hole; of a cover sheet of wax paper secured at one end to the outer end of the blade and of a length sufficient to extend completely over the blade and onto the handle.

In testimony whereof I affix my signature in presence of two witnesses.

HARRY F. SMITH.
